UNITED STATES PATENT OFFICE.

FREDERICK HEYL, OF NEW YORK, N. Y.

CLOTHESPIN.

1,330,320.

Specification of Letters Patent. Patented Feb. 10, 92.

Application filed May 24, 1919. Serial No. 299,554.

To all whom it may concern:

Be it known that I, FREDERICK HEYL, a citizen of the United States, and residing at New York city, New York county, and New York State, have invented certain new and useful Improvements in Clothespins, of which the following is a specification.

This invention relates to clothes pins and its object is to provide means in the well known wooden fork pin consisting of grooves or serrations to receive the rope or wire and more firmly grip the clothes to be secured thereto. These and other details and objects of the invention are more fully described in the following specification, set forth in the appended claims and illustrated in the accompanying drawings, wherein:

Figure 1 is a side view of the improved clothes pin.

Fig. 2 is a view at a right angle to the above.

Fig. 3 is a side view of a modified form of pin.

Fig. 4 shows another modification.

Fig. 5 shows the pin further modified.

The ordinary fork pin as heretofore constructed has two jaws whose inside faces are plane and from constant wear become so smooth that they fail to attain their object and work loose from the rope and clothes gradually, or when the wind causes an excessive flapping of the garments.

Various means have been attempted, and wire and metal pins have been adopted, to secure a firmer grip on the clothes and line but have been found undesirable on account of the tendency of the metal to tear the clothes or rust them, and the weight and cost are also undesirable features.

The present invention is of the usual type of wood and consists of the shank 5 and head 6 of ordinary construction, the shank 5 terminating in the similar resilient jaws 7, spreading toward their lower ends to afford ease in securing the pin on the fabric and line. The outer sides of the jaws conform with the original shape of the blank pin while the inner and opposite faces are provided with a series of grooves 8 of various dimensions and increasing in size or arc toward the lower end of the pin so as to adapt

it to the various sizes of ropes, the upper grooves fitting a small rope while larger ropes are received by larger grooves.

The grooves 8 are substantially arcs of circles and may be formed by boring holes in the blank pin before the division of the jaws is stamped out.

It is very evident that when the jaws are sprung over a rope so that the grooves partly fit around the same it will be very difficult to release the rope or garments on account of greater bearing surface being afforded and some force will be required to pull the pin loose.

In the modified form shown in Fig. 3 the grooves 9 do not face each other and correspond but each groove faces the opposite flat surface of the other jaw so that while the groove fits around one side of the rope the other side of the latter is pressed upon by the flat side of the other jaw insuring the permanent location of the pin if necessary. The grooves 9 may also be larger as they descend toward the lower end of the line to provide for the location of the latter on a rope of any size.

The grooves 8 and 9 need not be arcs of circles in shape but when found desirable may be angular notches of any degree to form a wedge shape groove to tighten the grip of the pin on the rope or clothes and may correspond in location on the jaws or be staggered. This construction is shown in Fig. 4.

It is obvious that other modifications or arrangements of the grooves may be resorted to without departing from the essential features above described or form the scope of the appended claims.

The pin may also have jaws with opposite points and grooves 11 and 10 on their inner faces as shown in Fig. 5 and the points will push the rope into the grooves.

What I claim as new is:

1. In a clothes pin, the combination of a head and shank, and diverging jaws having plane inner surfaces with staggered notches so arranged that the said notches of each jaw are opposite a plane surface of the opposite jaw.

2. In clothes pins, the combination of a

head and shank, and diverging jaws with flat inner and opposite surfaces and having staggered notches; each notch being located opposite a flat surface and the notches increasing in size toward the lower ends of said jaws.

In testimony whereof I have signed my

name to this specification in the presence of two subscribing witnesses, this 14th day of May, 1919.

FREDERICK HEYL.

Witnesses:

A. W. BAKER,

JAMES F. DUHAMEL.
